UNITED STATES PATENT OFFICE.

WARREN S. SMITH, OF STONE CHURCH, PENNSYLVANIA.

WAGON-BRAKE.

SPECIFICATION forming part of Letters Patent No. 372,873, dated November 8, 1887.

Application filed March 15, 1887. Serial No. 230,984. (No model.)

To all whom it may concern:

Be it known that I, WARREN S. SMITH, a citizen of the United States of America, residing at Stone Church, in the county of Northampton and State of Pennsylvania, have invented certain new and useful Improvements in Wagon-Brakes, of which the following is a specification, reference being had therein to the accompanying drawings.

10 This invention pertains to certain new and useful improvements in wagon-brakes; and it consists in the detailed construction, combination, and arrangement of the parts, substantially as hereinafter fully set forth, and particularly pointed out in the claims.

15 In the accompanying drawings, Figure 1 is a plan view of my invention. Fig. 2 is a side elevation thereof, and Fig. 3 is an enlarged detail view showing portions of my invention in 20 different positions.

25 In carrying out my invention I employ the ordinary hounds, A, connected at their rear ends to the vehicle-axle a, and upon these ends of the hounds is disposed the ordinary bolster, as shown.

30 B is the horizontally-disposed wagon-brake rod or bar, on the outer ends of which are secured by ordinary means shoes b b. This brake rod or bar is supported in hanger-plates 35 b', secured to the under side of the hounds, as shown in Fig. 2. To the center of this brake rod or bar is secured the forward end of a rod, C, which end of the rod is screw-threaded, and, after being passed through the aperture in said 40 brake rod or bar, is secured by an ordinary nut screwed thereon, as shown. The other rear end of this central rod, C, is secured by means of a nutted bolt to the short arm d of a main lever, D, which lever is fulcrumed in 45 a projecting two-armed plate, d', secured to the vehicle-axle a. Against this short arm of the main lever D bears the forward end of a strong spring, d'', secured at its other end to the front side of the vehicle-axle, the purpose of which will appear farther on.

50 Through a hollow bowl-like portion, e, of the main lever D is passed a small rod, the outer rear end of which has two short parallel arms, between which is pivoted the inner end of a 55 second smaller lever, D', the outer end of which projects beyond the end of the main lever D, and to this outer end of the smaller lever, D',

is secured a cord or chain, f, the purpose of which will appear farther on.

F is a ratchet-bar secured at one end to the 55 under side of one of the hounds and at its other end to the vehicle-axle a, as shown, and the upper horizontal surface of this ratchet-bar has the teeth or ratchets projecting forward, and at the rear end of said ratchet-teeth 60 is an inclined portion, f', the purpose of which will appear hereinafter.

The under side of the lever D has a tooth-like surface for engaging with the teeth of the ratchet-bar F, and the outer end of said lever 65 is of an approximately V shape, from the upper side of which projects rearwardly a finger, f'', the lower inner end of which is adjacent the upper end of a shoulder, g. A horizontally-disposed bar, G, is pivotally secured at its rear end 70 to the outer side of one of the hounds, and has a slot, g', formed therein, through which is passed a stud or pin for retaining this bar in position, which is normally on the upper portion of the projecting end of the lever D, as shown.

75 The normal action of the spring d'' is to press outwardly on the short arm of the main lever D, causing the outer end of the longer arm thereof to be at the rear end of the ratchet-bar, and when in this position the smaller lever, D', is forced upon the incline f' of the ratchet-bar, and the tooth-like portion of said main lever is held in engagement with the rear-most tooth of the said ratchet-bar.

80 By pulling on the cord or chain f, which in practice is extended to the driver's seat, the lever D' will be pulled on the shoulder g and in under the projecting finger f'' of the main lever D, and by this means said lever D will be pulled forward over the ratchet-teeth, thus 85 forcing back the rear end of the short arm, and through the agency of the central rod, C, the brake rod or bar, together with its shoes, is moved in the direction toward the vehicle-wheels. When the brake has been sufficiently 90 applied, the same is secured at that point by loosening the hold on the cord or wire f, which will cause the smaller lever, D', to drop from the shoulder g onto the ratchet-teeth, and by reason of a bevel, g'', formed on the upper forward edge of this lever, the same will be caused to fit slightly in under the rear incline of the V-shaped end of the main lever D. From this 95 it will be seen that when it is desired to re-

to release the brake the same can be readily effected by pulling on the cord or chain *f*, which will cause the V-shaped end of the main lever to be raised up on to the bevel *g*" of the lever *D* out of engagement with the ratchet-teeth, and the spring bearing on the short arm of the lever *D* will force both levers to the rear end of the ratchet-bar, the lever *D*' sliding up on the incline *f*' and the lever *D* engaging the rearmost tooth, as before described.

My invention is so constructed that the same is applicable to wagons of long or short gear, and the working of the device is in nowise affected by the extent of the load carried by the

vehicle to which applied. I do not restrict myself to the application of my wagon-brake to the rear wheels of a vehicle, as the same can with equal facility be applied to the front wheels thereof; and, further, if desired, that part of my invention embodying the main and small levers and ratchet-bar may be employed in connection with a railway-car or mill.

Having thus fully described my invention, what I claim, and desire to secure by Letters Patent, is—

1. The herein-described wagon-brake, comprising the brake rod or bar, the central connecting-rod, the main lever, the spring, the smaller lever, and the ratchet-bar, all arranged substantially as shown and described.

2. The combination, with the wagon-brake and connecting-rod, of the main lever having a V-shaped end and a projecting finger, the smaller lever engaging with said end of the main lever, the operating cord or chain, and the ratchet-bar, substantially as shown and described.

3. The combination, with the wagon-brake and the connecting-rod, of the pivoted main lever having a tooth-like surface, the spring bearing against the short arm of said lever, the smaller lever having a bevel, the ratchet-bar provided with an incline at one end, and the pivoted horizontal bar, all arranged substantially as shown and described.

4. The combination, with the brake rod or bar and the connecting-rod, of the main lever having the V-shaped end, the shoulder and projecting finger formed therewith, the pivoted smaller lever having a bevel, the ratchet-bar provided with an incline at its rear end, and the operating cord or chain, all constructed and arranged to operate in the manner substantially as shown and described.

In testimony whereof I affix my signature in the presence of two witnesses.

WARREN S. SMITH.
